Primary Examiner — Katherine Glennon(74) *Attorney, Agent, or Firm* — Womble Bond Dickinson (US) LLP(57) **CLAIM**

The ornamental design for a watch as shown and described.

DESCRIPTION

FIG. 1 is a front view of a watch showing my new design; and,

FIG. 2 is a front perspective view thereof.

The dash-dot lines in the figures represent unclaimed elements and form no part of the claimed design.

1 Claim, 2 Drawing Sheets(56)
